JOHN L. COOPER AND ELIAS A. MONROE, OF ELMIRA, NEW YORK.

Letters Patent No. 90,820, dated June 1, 1869.

IMPROVED SPRING-BED BOTTOM.

The Schedule referred to in these Letters Patent and making part of the same.

To all whom it may concern:

Be it known that we JOHN L. COOPER and ELIAS A. MONROE, of the city of Elmira, in the county of Chemung, and State of New York, have invented certain new and useful Improvements in Spring-Beds; and we do hereby declare that the following is a full, clear, and exact description thereof, reference being had to the accompanying drawings, and to the letters of reference marked thereon, which form a part of this specification, and in which—

Figure 1 represents a plan view;

Figure 2, a side view; and

Figure 3, an end view of our spring-bed.

Similar letters indicate like parts in all the figures.

Our invention relates to improvements in spring-beds; and to this end,

It consists in the employment of wires for cross-bars, by which means we are able to fasten all the joints firmly without the use of rivets, making use of the springs as fasteners, not only of themselves, but of all the joints of the frame.

Our invention further consists in the use of cross-rods or wires, at the end of the frame, by which the top of each end and side is fastened to the bottom of each opposite end and side, the object of which will be hereinafter fully described.

To enable others skilled in the art to which our invention appertains to make and use the same, we will now describe its construction and operation.

In the accompanying drawings—

A represents the frame, which consists of the parallel wires *a a* and the longitudinal wires *b b*. The parallel wires are first bent, at each end, over the edge of the frame, as seen in fig. 1. One end of the longitudinal wires is then secured to the edge of the frame, and passed over the first parallel wire, under

the next, and so on to the end of the frame, where it is secured by a similar bend to the edge of the frame. It will be observed that the first longitudinal wire and every second one passes over the first parallel wire, while the remainder pass under the first parallel wire. By this arrangement the wires are made partly secure.

B B represent spiral springs, the ends of which are bent over the point where the parallel and longitudinal wires cross each other, as seen in fig. 1, whereby the springs B B, and the wires *a a*, *b b*, are secured without the use of rivets, as is the case when iron straps are used.

D D represent diagonal wires, secured by a bend to the sides of the frame. These wires are placed at suitable distances apart, and are to prevent the bed from leaning over to either side.

E E represent similar diagonal wires, attached to the ends of the frame, to prevent the ends from leaning over.

Having thus fully described our invention,

What we claim, and desire to secure by Letters Patent, is—

A spring-bed bottom, consisting of frame A, parallel wires *a a*, longitudinal wires *b b*, diagonal braces D D, E E, and spiral springs B B, the whole being constructed, combined, and arranged substantially as and for the purpose specified.

In testimony that we claim the foregoing as our own, we affix our signatures, in presence of two witnesses.

JOHN L. COOPER.
E. A. MONROE.
